UNITED STATES PATENT OFFICE.

FREDERICK P. DUSTAN, OF SALAMANCA, NEW YORK, ASSIGNOR TO SHOSUM MANUFACTURING CORPORATION, OF SALAMANCA, NEW YORK, A CORPORATION OF NEW YORK.

DISPLAY RACK FOR SHOES AND THE LIKE.

Application filed December 2, 1927. Serial No. 237,297.

This invention relates to a display rack which has been designed more particularly for displaying shoes, but which may likewise be used for displaying other articles.

5 Its chief object is the provision of a device of this character which is constructed and arranged to reliably support the shoes in a position for effectively displaying them, and which provides for the showing of a 10 maximum number of shoes in a minimum amount of floor space.

Other objects of the invention are to provide a portable display rack of this character which is simple, compact and inexpensive in construction, and whose parts may 15 be readily dismembered and assembled for convenience in shipping.

In the accompanying drawings:—

Figure 1 is a front elevation of a shoe 20 rack embodying my invention. Figure 2 is an end view thereof, partly in section. Figure 3 is a horizontal section on line 3—3, Figure 1. Figure 4 is an enlarged transverse section on line 4—4, Figure 1.

25 Similar characters of reference indicate corresponding parts throughout the several views.

My improved shoe rack has been designed to stand in a substantially upright position on the floor and is of such a nature that it can be readily shifted about to suit the convenience of the merchant. To this end it consists of a suitable frame composed of spaced uprights 10, 10 of angle bars 30 or other appropriate material and curved outwardly at their lower ends to provide supporting feet 11. A brace 12, preferably of U-shape, is detachably connected at its upper end to the uprights by a jamb-nut 13 and thumb-screw 14, said brace being disposed to support the rack in a slightly rearwardly inclined position, as shown in Figure 2.

Attached to the front sides of the frame-uprights 10, by welding or otherwise, are a 45 plurality of horizontal supporting bars 15 arranged in parallel relation and, by preference, made of angle iron whose vertical flanges 16 engage flatwise against the uprights while their horizontal flanges 17 project forwardly therefrom. Mounted on each 50 of these bars are a series of shoe-rests 18 which are preferably made of wire bent into a substantially U-shape and which overhang 55 or extend forwardly from the bars to sup-

port the sole-portion of the shoe, the heel portion of the shoe engaging the vertical bar-flange. The rear ends of the legs 19 of the shoe-rests are offset or bent laterally outward, as indicated at 20 in Figure 3, and 60 terminate in upstanding lugs or projections 21 which are adapted to be inserted through openings 22 formed in the vertical flanges of the supporting bars for detachably hooking the shoe-rests in place. In applying the 65 shoe-rests to the supporting bars, each one is held in a tilted position while its legs are sprung together to allow the anchoring lugs 21 to be inserted into a corresponding pair of openings 22, after which it is swung 70 downwardly to the position shown in the drawings. In this position, those portions of the shoe-rest legs in front of their offset portions 20 rest by gravity on the front edge of the horizontal flange 17 of the supporting bar, while their upstanding legs 75 abut against the rear side of the vertical flange 16 of said bar. The offset portions 20 and lugs 21 prevent transverse displacement of the shoe-rests relative to their supporting 80 bars, and the engagement of said lugs with the vertical flange of its supporting bar and the point bearing of the shoe-rest legs 19 on the horizontal flange thereof positively retains the rest in its forwardly-inclined position shown in the drawings.

The legs 19 of the shoe-rest may be curved in the manner clearly shown in Figure 4 and the front portion of the shoe engages the cross bar of the wire-rest, while the rear portion thereof immediately in front of the heel rests on the vertical flange of the supporting bar 15 with the front face of the heel abutting against the rear side of said flange to prevent the shoe from slipping forwardly 95 off the rest. The lugs 21 of the latter project a sufficient distance above the top edge of the bar-flange 16 to constitute side abutments for preventing displacement of the shoe lengthwise of the bar. For the purpose of avoiding marring the shoes from contact with these lugs, the latter may be provided with sleeve-pads 23 of rubber or like material.

By the provision of a rack of this character, the entire shoe is effectively and attractively displayed so that the customer and salesman may readily select the particular style of footwear desired. Furthermore, the device is simple and compact requiring but 105 110

a minimum of floor space for displaying a maximum number of shoes, and it can be readily assembled and dismembered. While the invention is shown for use in connection with the showing of shoes, it will be understood that its structure is such that it is equally applicable for displaying other articles.

I claim as my invention:—

- 10 1. A display rack, comprising a frame including a supporting bar of angle shape in cross section, the vertical flange of said bar having a pair of openings therein, and a substantially U-shaped article-rest having its free ends detachably engaging said bar openings and terminating in upstanding lugs arranged to bear against the rear side of said vertical bar-flange, the article-rest bearing at a point intermediate its ends on the front edge of the horizontal bar-flange, said lugs extending above the top edge of said vertical bar-flange to form abutments between which the article is located.
- 15 2. A display rack, comprising a frame including a supporting bar of angle shape in cross section, the vertical flange of said bar having a pair of openings therein and the horizontal flange extending forwardly from the lower edge of said vertical flange, and a substantially U-shaped article-rest of wire mounted on the supporting bar and projecting forwardly therefrom, the legs of said rest being engageable with said bar open-

ings and provided adjacent their rear ends in front of said vertical bar-flange with laterally offset portions and the ends of the latter terminating in rear of said vertical flange in upstanding lugs arranged to bear against such flange, the legs of said rest bearing intermediate their front and rear ends on the front edge of said vertical bar-flange.

3. A display rack, comprising a frame including a pair of spaced uprights and a plurality of horizontal angle-bars mounted on said uprights, the vertical flange of each bar engaging said uprights and having pairs of openings therein and its horizontal flange facing forwardly, a brace for holding said frame in a substantially upright position, and a plurality of U-shaped article-rests of wire detachably mounted on said bars and extending forwardly therefrom, each of said rests having its legs engaging a pair of said bar-openings and being provided in front of such opening-engaging portions with lateral offset portions and terminating in rear of the former in upstanding lugs arranged to bear against the vertical bar-flange, those portions of the legs in front and adjacent to the offset portions resting by gravity on the front edge of the horizontal bar-flange, said lugs projecting above the top edge of the vertical bar-flange to form side abutments between which the article is located.

FREDERICK P. DUSTAN.
